UNITED STATES PATENT OFFICE

HENRY A. FINK, OF CHICAGO, ILLINOIS, ASSIGNOR TO CONTINENTAL CAN COMPANY, INC., OF NEW YORK, N. Y., A CORPORATION OF NEW YORK

DEVICE FOR TIMING AND FEEDING CONTAINERS

Application filed March 23, 1929. Serial No. 349,464.

The invention relates to new and useful improvements in devices for timing and feeding filled containers to a closing machine.

An object of the invention is to provide a timing device which includes traveling fingers disposed so as to engage the containers in a plane above the bottom ends of the containers but adjacent the same so that relatively small containers can be engaged and timed thereby.

A further object of the invention is to provide a timing device for containers having timing fingers which are so constructed and operated that the timing finger makes a non-shiftable contact with the face of the container.

These and other objects will in part be obvious and will in part be hereinafter more fully disclosed.

In the drawings which show by way of illustration one embodiment of the invention:

Fig. 1 is a plan view of a portion of a closing machine with the improvements applied thereto.

Fig. 2 is an end view of the same.

Fig. 3 is a side view of the supporting means for the timing chain and showing the immediate means for actuating the same.

In the Patent No. 1,628,919, granted Matthew M. Sedwick May 17, 1927 there is shown and described a mechanism for feeding filled containers to a closing machine wherein the containers are timed by means of a feeding screw. The containers are received promiscuously by a rotating disc which, as it travels, conveys the containers against the feeding screw and this feeding screw will retard and separate the containers and insure that they are delivered to the feed drum at the proper time to be taken by the thread of the drum.

The feed screw is necessarily arranged above the disc onto which the containers are received and as this feed screw is necessarily of considerable diameter the minimum height of the container which can be timed by this mechanism is limited. Furthermore, the timing screw has sliding contact with the container and this is apt to scratch and mar the decorated face of the container.

The present invention is an improvement upon the device shown in the Sedwick patent and consists in a traveling chain having timing fingers, which chain is so disposed as to pass over the disc onto which the containers are received. The traveling chain may be located close to the upper face of the disc. The timing fingers travel in a straight path over the disc and the line of travel forms a cord of a circular outline by the disc. There is a guide associated with the disc for directing the containers against the traveling chain. The finger is traveling in a straight path as it moves from behind the guide over the disc and is also traveling substantially in a straight path when the container is taken up by the thread of the drum. The fingers are mounted on a traveling chain moving in a horizontal plane. The chain runs over sprocket wheels mounted on suitable shafts which are driven from the shaft carrying the drum which receives and feeds the containers to the closing machine. The disc is also operated from the shaft actuated by the drum.

Referring more in detail to the drawings, the invention is shown as applied to a closing machine having a feed drum 1 provided with a spiral thread 2. The drum is associated with a supporting member 3 on which the container is in part supported, the container being in part supported by the drum and fed along the support by the thread on the drum. A guide rail 4 extending along the drum is provided for directing the containers in their forward travel. This feeding mechanism for receiving the containers and delivering the same to the closing machine is similar to that shown in the Sedwick patent and further detailed description thereof is not thought necessary.

The invention is not directed to the feeding mechanism which receives the timed containers and delivers the same to the closing machine, but rather to the devices for receiving the containers promiscuously and timing and delivering the same to this feeding mechanism. Instead of a drum feed such as shown any other type of feeding mechanism adapted to receive the timed containers and deliver the same to the closing mechanism may be 100

used. The containers are received promiscuously onto a disc 5 which is supported by a shaft 6 mounted in a suitable bracket 7 carried by the frame which supports the drum. This frame is supported in turn by the closing machine and by the standard 8 at the outer end thereof. The containers are indicated at C in the drawings. As the disc rotates the containers resting thereon will move with the disc. There is a guide rail 9 which overhangs the traveling disc 5. There are other guide rails not shown which direct the containers onto the disc and against the guide rail 9. There is also a guide rail 10 pivotally supported at 11 and moved through suitable devices by a weight 12 so that a lug 13 is yieldingly held in contact with the stop screw 14. The containers are directed by the traveling disc against the guide rail 9 and through the aid of the guide rail 10 will be caused to engage the timing devices.

The timing device consists of a traveling chain 15 carrying a series of fingers 16. Each finger 16 is provided with a face 17 which is substantially at right angles to the path of travel of the chain between the supporting sprockets therefor. The chain is supported at one end by a sprocket wheel 18. This sprocket wheel 18 is mounted on a bracket 19 carried by the frame supporting the drum 1. The chain is supported at its other end by a sprocket wheel 20. The sprocket wheel 20 is mounted on a short shaft 21 journaled in the bracket 19. At the upper end of the shaft is a bevel gear 22 which meshes with a bevel gear 23 on a shaft 24. The shaft 24 carries a sprocket wheel 25 at its outer end. The drum 1 is mounted on a shaft 26. On the other end of this shaft is a sprocket wheel 27. A driving chain 28 passes under the sprocket wheel 27 and over the sprocket wheel 25. This chain runs over an idler 29. On the shaft 6 is a worm gear 30 which meshes with a spiral gear 31 carried by the shaft 32. On the outer end of the shaft 32 is a sprocket wheel 33. The sprocket chain 28 also runs over this sprocket wheel 33. As the shaft 26 of the drum rotates it will impart rotation to the sprocket wheel 33 and the sprocket wheel 25. Thus it is that the disc 5 is rotated and also the timing chain 15 driven.

The guide rail 9 is so positioned that the timing finger 16 as it travels about the sprocket wheel 18 will be righted up so that the face 17 of the finger is substantially at right angles to the path of travel of the sprocket chain 15 across the upper face of the disc 5. This occurs before the finger comes from behind the guide rail 9. The path of movement of the timing fingers is a cord of the circle of the circumference of the traveling disc 5. The containers on the disc have imparted thereto a bodily movement in a circular path conforming to the circle of the circumference of the disc 5. The timing

70 fingers move in a straight path of travel across the disc as noted, and will, therefore, have a uniform speed of travel. The container as it is moved by the disc from the position shown at C to the position shown at C' is traveling in a direction toward the timing chain and also in a direction with the direction of travel of the timing chain. The speed of movement of the container toward the chain gradually decreases until the container reaches a line passing through the center of rotation of the disc at right angles of the chain.

75 As the container moves to the position shown at C' its speed of travel increases slightly as the container is shifted outward on the disc by the guide rail 10. As the container moves to the position shown at C² it is moved still further out on the disc, but the portion of the disc on which the container rests is moving at a greater speed away from the chain and, therefore, the movement imparted to the container by the disc is retarded.

80 The containers will, therefore, be placed against the chain and carried against the rear face of the finger 16 when the position indicated at C² is reached. These timing fingers are relatively close together so that there is ample room for the container between the fingers with a slight freedom of movement so as to avoid any rubbing or scratching contact between the fingers and the container. As the container continues its movement it will be placed against the front face of the timing finger 16 and this is the fully timed position 85 of the container. The finger then becomes the active feeding element for presenting the container to the feed drum or the feeding mechanism which receives and delivers the same 90 to the closing machine. If the container should strike against the end of the finger the guide rail 10 will yield and allow it to pass in rear of the finger or force it in front of the finger so that it will be positioned 95 against the chain. This engagement with the end is not the usual action of the containers. The container C' which is placed in between the timing fingers will hold back the container C so that it will pass behind the finger 16. 100 The fingers are traveling in a straight path in 105 a forward direction when they become active in the timing of the containers. The containers are really carried against the rear face of the timing fingers at the first portion of the travel of the fingers while controlling the containers, and then the container will be placed against the front face of the timing fingers and conveyed to the feed drum. The finger has substantially no sliding contact 110 with the container and, therefore, the decorated surface of the container will not in any way be scraped or disturbed. These fingers 115 can travel very close to the disc and, therefore, containers which are very low in height may 120

125 130

be readily received and timed by this timing device.

The disc at the point of tangency with the line of feed of the containers by the feed drum 1, which line is controlled by the guide rail 4 is traveling faster than the feed of the closing machine. The timing fingers move in a path parallel with the line of feed of the closing machine and at substantially the same speed as the feed of the closing machine.

From the above it will be apparent that the container is received onto the rotating disc promiscuously and carried thereby against the timing chain. The chain is disposed so that it is substantially tangential to the path of movement given to the containers by the disc so that the containers move in a circular path until they contact with the chain, then in a tangential path as they follow along with the chain. At this point of tangency where the container starts on its straight travel the fingers of the chain are moving slightly slower than the disc. At this point or slightly following this point, the container will be carried against the rear face of the finger and the finger of the chain will retard the travel of the container, thus bringing about a spacing of the containers. As the container moves along in a straight path of travel conveyed by the rotating disc, the resultant speed of travel imparted to the container by the disc gradually decreases as all points of the disc are traveling in a curved path away from the straight line of travel of the container at this time. As a result the container continues to move but its movement is retarded to such an extent that it is engaged by the front face of the following timing finger on the chain. This timing finger now positively transfers the container from the disc across the stationary portion of the frame into range of the thread on the drum. Thus it is that the containers are spaced and timed by these timing fingers which have a straight path of travel just above the disc so that a very low container may be engaged and timed thereby and the timing fingers do not make any rubbing contact with the face of the container so as to injure the decoration thereof.

It is obvious that minor changes in the details of construction and the arrangement of the parts may be made without departing from the spirit of the invention as set forth in the appended claim.

Having fully described my invention what I claim as new and desire to secure by Letters Patent, is:—

A mechanism for feeding filled containers in predetermined spaced relation and in proper timing to a closing machine comprising a rotating disk adapted to receive containers at random, an endless flexible member traveling over said disk in a direction substantially parallel with the line of feed to the closing

machine, and outside the path of travel of the containers on the disk, guide rails associated with the disk for directing the containers, one at a time, against the flexible member, fingers carried by the flexible member and spaced apart a distance sufficient to receive therebetween a container, the forward faces of said fingers being at right angles to the line of feed and the rear faces of said fingers being inclined to the line of feed so as to permit of the containers being closely spaced as they are fed by the flexible member, said fingers being timed so as to deliver the containers to the closing machine feed, and means for operating said disk and said fingers so that the disk at the point of tangency with the line of feed travels slightly faster than said fingers, whereby the container will be first carried against the rear face of the fingers for spacing and timing the containers while the following finger delivers the container to the feed for the closing machine.

In testimony whereof, I affix my signature.
